H. G. MILLER

COLLAPSIBLE VEHICLE TOP

Filed Dec. 30, 1925

UNITED STATES PATENT OFFICE.

HAROLD GORDON MILLER, OF HOMER, NEW YORK, ASSIGNOR TO THE BREWER-TITCHENER CORPORATION, OF CORTLAND, NEW YORK, A CORPORATION OF NEW YORK.

COLLAPSIBLE VEHICLE TOP.

Application filed December 30, 1925. Serial No. 78,352.

This invention relates more particularly to automobile tops of the so-called "one-man clear-vision" type and is characterized by the use of an improved disposition of an articulated bipartite main bow, of which the rear member or section is pivotally carried by the respective support standards in cantilever fashion through the medium of a pair of complementary links attached to each side 5 rail of said cantilever bow section, while the extreme forward or outrigger section is pivotally adjoined to the free ends of said rails to constitute a closed loop, such that when the top is placed in open or extended 10 position, both of the bipartite bow sections will extend in a substantially aligned relation over the trim line of the vehicle body.

The object of the present invention is the adaptation of such bipartite bow or hoop for 15 support by a single set of rearwardly inclined support standards pivoted to the respective body sides, and to provide suitable guide linkage means whereby the indicated extended outrigger section may readily be 20 collapsed alongside its standards. The present invention is more largely directed toward a top frame work requiring a relatively long overhung span preferably resting between said rear standards and the wind- 25 shield stanchions of the car, especially such tops as may be applied to the phaeton type of automobile body.

In the present embodiment, the main bow 30 comprises an outrigger and a cantilever 35 hoop section and each such section is preferably made essentially U shaped and provided with relatively long leg or rail ends. The crown or transverse element of the first named or forward bow section may be disposed along the front of the top while the 40 crown of the last named bow section preferably defines the rear edge of the top, the respective leg ends of said bipartite bows being directed toward each other and pivot- 45 ed together by a rule joint or other suitable type of knuckle stop means. This bipartite structure as pivotally mounted about the supporting standards, may be counterpoised by means of strainer straps or the like.

50 There are also provided a plurality of supplemental bows, the ends thereof being preferably pivoted to the cantilever section of the bipartite bow along their respective

side rails. In conjunction with such supplemental bows, interconnecting slot link means 55 are used to pivotally tie up these bows with the outrigger section and likewise with the support standards, whereby the top structure may either be folded or extended without dependence upon the fabric cover for 60 giving coordinated movement to the component top members as a whole.

A further feature of the present invention resides in upwardly projecting one of each 65 set of the indicated guide links beyond the level of the raised cantilever bow section, and each of these projections is preferably equipped with a rule joint adapted to carry the complementary leg ends of one of my supplemental bows.

70 Embodied herein are further features of structure and organization to accomplish the foregoing and related purposes, all of which will be set forth in detail hereinafter.

75 Reference is had to the annexed one sheet drawing which is illustrative of a specific embodiment of my invention, like characters of reference indicate like parts throughout the several views; and in which drawings:

Fig. 1 shows a sectional elevational view as 80 seen from the interior of a top supporting structure embodying my improvements as applied to an automobile body, the top being here shown in its raised or extended position.

Fig. 2 is a fragmental side view in partial 85 section indicating the relation assumed by the top elements when in a partially collapsed or folded condition.

Fig. 3 is a view similar to Fig. 2 and shows the position occupied by the top elements after the structure has been collapsed 90 into its fully collapsed position.

Fig. 4 represents an enlarged detail of certain top parts as taken in section along line 4-4 of Fig. 1.

95 The term "bow or hoop" is herein used to designate not merely the usual wooden bow but is inclusive of the metallic socket or slat iron elements that are conventionally attached to the legs thereof. While the drawings merely show the structure required to complete one side of my top, it will be manifest that this same mechanism is to be provided in duplicate for the other side of the vehicle body and that the transverse 100 bow crowns are intended to bridge said sides 105

to form a unitary top structure adapted to support and mount the cover fabric.

Referring now in detail to the drawings, the cover fabric designated in its entirety by the numeral —1—, is appropriately stretched over said top structure in the customary manner, the frame work in the present disclosure being shown as constructed of rectangular slat irons instead of the more usual tubular bow sockets. The top structure as a whole is primarily supported by a single set of standards such as —2—, which are respectively pivoted upon the outer sides of the body or tonneau —3— by means of the props or fulcrum irons such as —4—. Said standards are preferably inclined rearwardly and upwardly in the direction of the rear corner of the top but said standards may be cut off in the manner indicated in Fig. 1. The free upper end portion of each such shortened standard is equipped with a suitable pivot —5— which mounts the guide link —6—. In raised top position, said link is preferably inclined upwardly and forwardly with respect to the standard —2—, while the other end portion of the link —6— is provided with a pivot —7— which carries the cantilever section of my articulated bipartite bow and holds the level of the raised main bow in spaced relation to said upper ends of the standards and it will be observed that said link 6 is preferably of the rigid or inflexible type having no collapsible joints disposed between the fulcrums 5 and 7. This cantilever hoop section is designated in its entirety as —8—, and comprises two leg or side rail elements such as 8^A, and when the top is extended, these side rails are intended to lie in a level above the raised ends of the standards and in a plane substantially parallel to that of the respective longitudinal trim line —3^B— of the body sides, while the connecting crown member —8^B— is overhung rearwardly of the standards and preferably lies directly above the transverse body trim line —3^A—.

Each of the free ends of the cantilever rails such as —8^A—, is provided with a rule or other suitable knuckle stop joint means —8^C— adapted to break downwardly as indicated. The respective joints carry the cooperating free end of the bow legs —9^A— of the outrigger bow section designated in its entirety by —9—. This bow —9— is likewise provided with a transverse crown portion —9^B— which is disposed along the front edge of the top.

Referring further to the novel linkage which serves to pivotally support my bipartite bow sections —8— and —9—, it will be observed that the first named section —8— is pivotally mounted so that the rails are made to extend rearward of the standards in cantilever fashion. In addition to the described guide link —6— there is also pro-

vided a complementary brace link —10— of which one end portion is joined to one of the cantilever side rails —8^A— by the pivot —11—, while the other end of the rearwardly and downwardly disposed link —10— is joined to one of the standards —2— intermediate the ends thereof by the pivot —12—, which fastening can readily be disposed in ample spaced relation to the upper standard pivot —5— to impart rigidity and give the desired bracing effect to the long overhung bipartite outrigger bow section —9—.

The described linkage hook up for swinging the cantilever section —8— alongside of the respective standards for collapsing purposes, is substantially that of a polygon drag type comprising the following four pivoted link elements, viz: a portion of the cantilever rail embraced between the pivots —7— and —11—; an oppositely disposed link embraced between the pivots —5— and —12—; the transversely disposed guide link —6—; and finally the brace link —10— which completes said polygon.

It is pointed out that the two last named links, that is to say —6— and —10— are disposed wholly forward of the standard —2—, and that such double complementary link ties extending between the cantilever section —8— and the standard, act conjointly as a unitary means to guide the former into either its collapsed or extended position with respect to the latter. Furthermore, as is shown in Figs. —2— and —3—, both rail ends of said links —6— and —10— are made to swing upward about their respective spaced pivots —5— and —12— and away from the standard fulcrum prop —4—. Thus when the cantilever section —8— is fully collapsed, its side rails will be brought into juxtaposition alongside the respective standards while the links —6— and —10— assume a common oblique relation crosswise of the standard in the fashion indicated by Fig. 3. During the collapsing operation the relatively long bipartite bow sections —8— and —9— are drawn toward the outer free extremity of the standard —2— and when the top parts finally reach their fully collapsed positions, the rule joint —8^C— may be made to shift back of the body fulcrum iron —4— in the manner shown in Fig. 3.

In connection with the described cantilever fashion of mounting for the rear bow section —8—, it is expedient to utilize the strainer straps —1^C— preferably fastened to the transverse overhung bow crown —8^B— and the rear body trim line —3^A— as shown in Fig. 1, and it will be apparent that the strainers serve as reinforcements to relieve the pull that would otherwise come upon the rear cover fabric 1^B. It is also preferred to draw the forward portion of the outrigger bow section —9— down

against the windshield stanchion —2^A to provide for supplemental top support means in the customary manner.

My top may further be equipped with one or more supplemental bows, preferably disposed to bridge the side rails of the cantilever section —8—. To this end each guide link such as —6—, may be made to project upward beyond the upper edge of the raised side rail —8^A— and provide for the link extension —6^A—, of which the outer free end is equipped with a rule or other suitable knuckle joint means —13^A—. To these complementary extensions are attached the respective leg ends —13^B— of supplemental bow —13— and the connection therewith is preferably made in such fashion that said rule joint is allowed to break downwardly when the top is set up in raised position, said bow legs —13^B— then lying in substantial alignment with the link —6— and disposed to project forwardly and upwardly with respect to the link pivot —7—.

The purpose of said rule joint —13^A— is in part to facilitate a snug collapsing of the top members, and in Fig. 3, certain of the links are shown as broken away in order to better illustrate that said rule joint —13^B— is allowed to partially open and bring the bow —13— into close juxtaposition between the adjacent cantilever sections —8— and —9—. In certain top layouts, it might be deemed expedient to dispense with the supplemental joints —13^A—, especially so when the conditions are such as will still allow of sufficiently close crashing without encountering undue interference with the members of the top frame.

Fig. 4 discloses in detail, the preferred lateral disposition of my linkage arrangements. It will be seen that one end portion of the brace link —10— may be mounted adjacent to the inner slat iron face of the cantilever side rails —8^A— while the other end thereof may be pivoted to the inner side face of the standard —2—. The guide link —6— is similarly disposed and is preferably made to lie in a common vertical plane with that of the brace link —10— such that the slat iron of the side rail —8^A— and the standard —2— are made to fall into substantial alignment. To this end, the rear transverse bow leg —13^B— is preferably secured to the outer face of its slat iron which in turn is attached to the rule joint —13^A—, while the leg end of wooden crown member —8^B— may be attached to the outer face of the slat iron rail element of the cantilever that projects rearward from the rule joint —8^C—.

The leg end —14^B— of the forward supplemental bow —14— may be mounted directly upon the cantilever rails —8^A— by the pivots —14^A— and these joints are preferably placed intermediate the joint

—8^C— and the rear supplemental bow pivots —7—, and in the raised position of the top, said bow —14— will be inclined in a substantially parallel relation to that of the complementary rear bow —13—.

These supplemental bows may be interconnected with respect to the outrigger section —9— in lazy tong fashion by means of suitable lever straps or slot links as shown in Fig. 1, the rear link —15— being pivotally connected to the bow leg —13^B— at the point —15^A— and thence extending forwardly to the pivot —15^B— carried by the bow leg —14^B—. A second or forward link —16— similarly connects the pivot —16^A— with the pivot —16^B—, the latter being carried by the outrigger leg —9^A— and thus serves to impart concordant action to all of the component top elements while they are being manipulated.

Having described the details of my top structure, it is thought that the mode of operation will readily be understood from the showing of the top in its several stages of collapse. It will be observed that by virtue of the system of links —15— and —16—, the top may be folded as a unit by lifting the outrigger crown —9^B— to break the rule joint —8^C—, which in turn will actuate the described polygon linkage in unison with such movement and concurrently cause the rule joint —13^A— to break therewith, said joint —8^C— being made to swing backwardly and downwardly toward the fulcrum iron —4— as indicated in Fig. 2. In their completely collapsed position, the top members assume the folded relation shown in Fig. 3, when said knuckle joint —8^C— will be drawn lengthwise of the support standard —2—, and the end —11— of the brace link —10— and the rule joint end of the guide link —6— will then be directed outwardly and away from the standard fulcrum —4—, all without allowing any of the bow elements to drop below or come into contact with the adjacent body parts during the crashing operation, a feature which obviates marring or otherwise defacing the body finish.

Another advantage inherent in my improved top structure resides in fewness of the parts as applied to long span tops and the compactness with which it is possible to collapse this improved type of top. This objective is furthered by the use of the rule joint —13^A— since this allows of swinging downward and breaking the overhanging portion of the crashed supplemental rear bow —13— and thus serves to effect a close disposition of the collapsed bow members. As a further advantage, the bow —13— in its open position may be given any desired inclination with respect to the cantilever side rails —8^A— irrespective of the corresponding angle given to the raised link —14—.

—6—, but still permitting said bow to be disposed to advantage when the top is collapsed.

As previously indicated, the outrigger section —9— of my top is intended to be secured to the windshield stanchion —2^A— or the like supplementary forward support and when the top is raised, the rear strainer tension straps such as —1^C— maintain a downward pull upon the overhung cantilever crown member —8^B—, the unbalanced moment exerted by such straps being taken up through the locked rule joints —8^C— and —13^A—, which in turn is counterpoised by a downward pull at the stanchion —2^A—, any incidental adjustment on part of the top frame being provided for with respect to the standard —2— through the medium of the described polygon linkage. In its raised position, said linkage is therefore securely locked with respect to the body fulcrum —4— and the top framing as a whole presents an unusually rigid and staple structure and particularly so against any downwardly thrust that may be imposed at the jointed leg members —8^A— and —9^A— or aiming to break the bow lock joint —13^A—. Furthermore, an exceptionally low deck quarter depth can be attained with my improved top arrangement and this feature imparts a stylish and otherwise distinctive appearance to long span tops.

Although a specific embodiment and shape of top structure have herein been described in detail, I do not wish to be limited to any particular arrangement or form of parts, since various changes may be resorted to, all without departing from the spirit and scope of my invention, heretofore described and more particularly pointed out in the appended claims.

Claims—

1. In a collapsible top frame for vehicle bodies and the like, the combination of a bipartite main bow comprising an outrigger hoop section and a cantilever hoop section, the latter having a pair of side-rails pivotally adjoined to the legs of the outrigger hoop and adapted to extend in substantial alignment therewith when raised over the body; a set of support standards pivotally connected to the respective sides of the body, the upper ends of the standards being kept below and spaced from the raised side-rails; a guide-link for each side-rail which link is pivoted to its respective rail intermediate said rail ends and is disposed to project upwardly above its rail to provide an extension while another portion of the guide-link is pivotally connected to said upper end portion of its support standard; a brace-link for each side-rail which link is pivotally attached to its adjacent standard between the aforesaid guide-link pivot and the body pivot of the standard and also pivoted to its side-rail forwardly of the guide-link pivot, said guide and brace links with their respective side rail and standard constituting a polygon type of linkage adapted to conjointly guide the cantilever section into collapsed position alongside its respective support standard; a supplemental bow bridging said side-rails, the legs of said bow being pivotally connected to the respective extensions; and link means interconnecting the supplemental bow with the outrigger section.

2. In a collapsible top frame for vehicle bodies and the like, the combination of a bipartite main bow comprising an outrigger hoop section and a cantilever hoop section, the latter having a pair of side-rails pivotally adjoined to the legs of the outrigger hoop and adapted to extend in substantial alignment therewith when raised over the body; a set of support standards pivotally connected to the respective sides of the body, the upper ends of the standards being kept below and spaced from the raised side-rails; a guide-link for each side-rail which link is pivoted to its respective rail intermediate the rail ends and projects upwardly beyond said raised rail to serve as an extension, while another portion of the guide-link is pivotally connected to the end portion of its support standard; a brace-link for each side-rail which link is pivotally attached to its adjacent standard between the aforesaid guide-link pivot and the body pivot of the standard and also pivoted to its side-rail forwardly of the guide-link pivot, said guide and brace links with their respective side rail and standard constituting a polygon type of linkage adapted to conjointly guide the cantilever section into collapsed position alongside its respective support standard; a supplemental bow bridging said side-rails, the legs of said bow being pivotally connected to the respective extensions; and link means interconnecting the supplemental bow with the outrigger section serving to counterpoise said strap pull.

3. In a collapsible top frame for vehicle bodies and the like, the combination of a bipartite main bow comprising an outrigger hoop section and a cantilever hoop section, the latter having a pair of side-rails pivotally adjoined to the legs of the outrigger hoop and adapted to extend in substantial alignment therewith when raised over the body; a set of support standards pivotally connected to the respective sides of the body, the upper ends of the standards being kept below and spaced from the raised side-rails; a guide-link for each side-rail which link is pivoted to its respective rail intermediate the rail ends and projects upwardly beyond said raised rail to serve as an extension, while another portion of the guide-link is pivotally connected to the end portion of its support standard; a brace-link for each side-rail which link is pivotally attached to its adjacent standard between the aforesaid guide-link pivot and the body pivot of the standard and also pivoted to its side-rail forwardly of the guide-link pivot, said guide and brace links with their respective side rail and standard constituting a polygon type of linkage adapted to conjointly guide the cantilever section into collapsed position alongside its respective support standard; a supplemental bow bridging said side-rails, the legs of said bow being pivotally connected to the respective extensions; and link means interconnecting the supplemental bow with the outrigger section.

4. In a collapsible top frame for vehicle bodies and the like, the combination of a bipartite main bow comprising an outrigger hoop section and a cantilever hoop section, the latter having a pair of side-rails pivotally adjoined to the legs of the outrigger hoop and adapted to extend in substantial alignment therewith when raised over the body; a set of support standards pivotally connected to the respective sides of the body, the upper ends of the raised standards being kept below and spaced from the side-rails; a guide-link for each side-rail which link is pivoted to its respective rail intermediate the rail ends to project upwardly beyond

said raised rail to serve as an extension, while another portion of the guide-link is pivotally connected to said upper end portion of its support standard; a brace-link for each side-rail which link is pivotally attached to its adjacent standard between the aforesaid guide-link pivot and the body pivot of the standard and also pivoted to its side rail forwardly of the guide-link pivot, said guide and brace links being adapted conjointly to guide said cantilever section into collapsed position alongside the respective standards; a supplemental bow bridging the side-rails, the legs of said bow sloping obliquely downwardly and rearwardly toward the raised side-rails and being pivotally connected to the respective extensions by knuckle stop-joint means adapted to break downwardly out of their raised position, and link means interconnecting the supplemental bow with the outrigger section adapted to break said bow stop-joint concurrently with the initial lifting of the aligned outrigger section and thereupon imparting concordant movement to all the component top elements between their extended and collapsed positions, the opening of said bow stop-joint allowing said supplemental bow to adjust itself into snug juxtaposition when interposed between the main bow sections in collapsed top position.

4. In a collapsible top frame for vehicle bodies and the like, the combination of a bipartite main bow comprising an outrigger hoop section and a cantilever hoop section, the latter having a pair of side-rails pivotally adjoined to the legs of the outrigger hoop and adapted to extend in substantial alignment therewith when raised over the body, a set of support standards pivotally connected to the respective sides of the body, the upper ends of the standards being kept below and spaced from the raised side-rails; a guide-link for each side-rail which link is pivoted to its respective rail intermediate said rail ends and projects upwardly beyond the raised rail to serve as an extension, while another portion of the guide-link is pivotally connected to the upper end portion of its support standard; a brace-link for each side rail which link is pivotally attached to its adjacent standard between the guide-link and the body pivot of the standard, while another portion of the brace-link is pivoted to its side-rail forwardly of the guide-link pivot, said guide and brace links being disposed wholly forward of the standards and serving conjointly to guide said cantilever section into collapsed position along-side the respective standards; a supplemental bow bridging said rails, the leg ends of said bow being secured to the respective extensions; and link means interconnecting the supplemental bow with the outrigger section serving to impart concordant action to all com-

ponent top elements between their extended and collapsed positions.

5. In a collapsible top frame for vehicle bodies and the like, the combination of a bipartite main bow comprising an outrigger hoop section and a cantilever hoop section, the latter having a pair of side-rails pivotally adjoined to the legs of the outrigger hoop and adapted to extend in substantial alignment therewith when raised over the body, a set of support standards pivotally connected to the respective sides of the body, the upper ends of the standards being kept below and spaced from said level of the side-rails; a guide-link for each side-rail which link is pivoted to its respective rail intermediate said rail ends and projects upwardly beyond the raised rail to serve as an extension, while another portion of the guide-link is pivotally connected to said upper end portion of its support standard; a brace-link for each side-rail which link is pivotally attached to its adjacent standard between the aforesaid guide link pivot and the body pivot of the standard and also pivoted to its side-rail forwardly of the guide-link pivot, said guide and brace links being disposed wholly forward of the standards and adapted conjointly to guide said cantilever section into collapsed position alongside the respective standards whereupon said rail ends of both the brace and guide-links will in consequence be directed outwardly and away from the respective standard body pivots and assume a substantial parallel relation disposed obliquely of the collapsed standards; a supplemental bow bridging said side-rails, the legs of said bow being connected to the respective extensions; and link means interconnecting the supplemental bow with the outrigger section.

6. In a collapsible top frame for vehicle bodies and the like, the combination of a bipartite main bow comprising an outrigger hoop section and a cantilever hoop section, the latter having a pair of side-rails pivotally adjoined to the legs of the outrigger hoop and adapted to extend in substantial alignment therewith when raised over the body; a set of support standards pivotally connected to the respective sides of the body, the upper ends of the standards being kept below and spaced from said level of the raised side-rails; a guide-link provided for each side-rail which link is pivoted to its respective rail intermediate said rail ends and projects upwardly beyond the raised rail to serve as an extension, while another portion of the guide-link is pivotally connected to the said upper end portion of its support standard; a brace-link for each side rail which link is pivotally attached to its adjacent standard between the aforesaid guide link pivot and the body pivot of the standard and also pivoted to its side-rail for-

wardly of the guide-link pivot, said guide and brace links being disposed wholly forward of the standards and serving conjointly to guide said cantilever section into collapsed position alongside the respective standards; a rear supplemental bow bridging said rails, the leg ends of said bow being pivotally connected to the respective link extensions by stop-joint means; a second or forward supplemental bow also bridging said rails, the leg ends thereof being pivotally connected to the respective rails; and link means interconnecting both the rear and forward supplemental bows with the outrigger section serving to impart concordant action to all the component top elements between their extended and collapsed positions.

7. In a collapsible top for vehicle bodies and the like, the combination of a bipartite main bow comprising an outrigger hoop section and a cantilever hoop section, the latter having a pair of slat-iron side-rails pivotally adjoined to the legs of the outrigger hoop and adapted to extend in substantial alignment therewith when raised over the body, a set of support standards pivotally

connected to the respective sides of the body and disposed in vertical alignment with the respective side-rail slat irons, the upper ends of the standards being kept below and spaced from the raised side-rails; a guide-link for each side-rail of which link one portion is pivoted against the inner face of one slat-iron rail intermediate the rail ends and projects upwardly beyond the raised side rails to serve as an extension, while another portion of the guide-link is pivotally connected to said upper end portion of its adjacent standard; a brace-link for each of said rails which link is also pivoted against the inner face of its slat-iron rail but forwardly of said guide-link pivot to fall into substantial vertical alignment with its respective guide-link; a supplemental bow bridging said side-rails, the legs of said bow being respectively pivotally connected to the respective link extensions; and link means interconnecting the supplemental bow with the outrigger section.

In testimony whereof, I have herewith set my hand this 29th day of December, 1925.

HAROLD GORDON MILLER.
